UNITED STATES PATENT OFFICE.

MYRON A. SMITH, OF NEW YORK, N. Y.

DEVICE FOR MARKING WITH PLASTIC MATERIAL.

1,147,982.

Specification of Letters Patent. Patented July 27, 1915.

Application filed November 20, 1908. Serial No. 463,523.

To all whom it may concern:

Be it known that I, MYRON A. SMITH, a citizen of the United States, residing at New York, in the county of New York and State of New York, have invented certain new and useful Improvements in Devices for Marking with Plastic Material, of which the following is a specification, reference being had therein to the accompanying drawing.

My invention relates especially to means and mechanism for forming a ridge or marking of plastic material such as chocolate upon the surface of confectionery, and the like, and has for its object the provision of a device of this character which shall be very effective in operation.

To attain the desired end, my invention consists essentially in the combination with a machine for applying coating material to centers, of a plastic material marking device in which is comprised a distributor, means for supplying a flow of marking material to said distributor, and means for imparting movement to the distributor; and my invention also involves certain other novel and useful combinations and arrangements of parts and peculiarities of construction and operation, all of which will be hereinafter first fully described and then pointed out in the claims.

In the drawings, Figure 1 is a side elevation and partial vertical section of a machine to which my plastic material marking mechanism is applied. Fig. 2 is an enlarged vertical, sectional view at line *a—a* of Figs. 4 and 6, and Fig. 3 is a like view at line *b—b* of the same figures. Fig. 4 is a plan view of the marking device removed from the machine and Fig. 5 is a front elevation thereof. Fig. 6 is a plan view of the mechanism for imparting movement to the marking device.

Similar numerals of reference, wherever they occur, indicate corresponding parts in all the figures.

I have illustrated my marking device as applied to a coating machine, the subject matter of United States Letters Patent 905,472, issued to me December 1st, 1908, but it is obvious the device is not limited to use with this specific machine.

In the drawings, 1 is the bed of the machine.

2 is a receptacle for plastic material,

mounted over a hopper 3 whereunder passes a carrier 4.

5 is one of a pair of standards extending upward above the bed 1.

6 and 7 are shafts mounted in the standards 5. Extending downward from the shaft 6 is an arm 8, the lower extremity whereof engages a rod 9 whereon is mounted a crank, the arm 10 of said crank carrying a wheel 11, and the arm 12 having a connecting rod 13 pivoted thereto. The wheel 11 is arranged to contact with a finger 14 mounted in a bracket 15. The rod 9 engages a horizontally movable bar 16 carrying a bracket 17 wherein is a slot 18.

19 is a trough provided at each end with trunnions 20 arranged to enter the slots 18 in the brackets 17. This trough is provided with perforations 21 in its bottom for the escape of flowing material, the quantity permitted to pass therefrom being regulated by means of a plate 22 carried by arms 23 extending from a rod 24 journaled at the top of the trough.

25 are springs which normally turn the rod 24 to move the plate 22 over the perforations 21, and 26 is an arm fixed to the rod 24 wherewith a regulating thumb screw 27 engages.

28 is a longitudinal bar provided with blades 29 which extend downward within the trough 19. At the front of the trough 19 is shown a downwardly extending plate 30 provided with a jacket 31 for the application of heating means. 32 are guides fixed to the trough 19.

33 are depending tongues mounted to swing in perforations in a material supply tube 34 leading from a trough 35 located beneath the material receiver 2.

36 is a finger on the bar 28 which engages a rod 43 pivoted at 37 and engaging a vertical bar 38 movably mounted on an arm 39 fixed on the shaft 6. The upper end of the bar 38 bears a stud 40 carrying a wheel 41 which bears upon the face of a cam 42 on the shaft 7. Fixed to the trough or distributor is a finger 55 which loosely engages a bar 44 pivoted at 45.

46 is a vertical bar extending from the bar 44 and pivoted at 47 to an arm 48 on the shaft 6. The upper end of the bar 46 bears a stud 49 whereon is a wheel 50 which bears against the face of a cam 51 on the shaft 7.

52 is the cam on the shaft 7 arranged to actuate the arm 8 through the medium of a contact wheel 53 carried by said arm.

In operation, flowing material being supplied to the distributing trough 19 through the pipe 34 and by tongues 33 depending from the perforations therein, is kept agitated by means of the blades carried by the rod 28 and its connections to the cam 42. When goods to be marked or decorated are carried beneath the distributor, the same may be caused to make a straight mark, or such mark may be made wavy or serpentine by the use of a cam having a face like the cam 42 being used in the place of cam 51, the rotation of such cam causing the distributor to vibrate longitudinally as the goods pass beneath it. By the use of cam 51, a curved line is deposited on the goods; and by the use of said cam 51 and a cam 52 having a periphery as indicated by the dotted line in Fig. 1 of the drawing, a circle of the marking material will be deposited on the goods for the reason that while the distributor is given a longitudinal movement by the cam 51, the cam 52 will move said distributor at right angles to the first mentioned movement through the medium of the arm 8, which actuates the bars 16 carrying the brackets which support the distributor.

Having now fully described my invention, what I claim as new therein, and desire to secure by Letters Patent, is:

1. The combination with a machine for applying coating material to the bodies of centers, in which is comprised a holder for coating material and means for moving centers to be coated beneath said holder, of a marking device, located in proximity to the body-coating mechanism, for automatically distributing marking material upon the surfaces of the goods after their bodies have been coated, and while such body-coating is in a plastic state and means for supplying material to the marking device.

2. The combination with a machine for applying coating material to centers, in which is comprised a holder for coating material and means for moving centers to be coated beneath said holder, of a marking device, located in proximity to the body-coating mechanism, and consisting of a material distributor for automatically applying marking material to the surfaces of the goods after their bodies have been coated, and while the body-coating is in a plastic state, means for supplying material to the marking device and means for operating the marking device.

3. The combination with a machine for applying coating material to the bodies of centers, in which is comprised a holder for coating material and means for moving centers to be coated beneath said holder, of a marking device, located in proximity to

the body-coating mechanism, and consisting of means for applying a flow of coating material to a distributor, and means for imparting movement to the distributor.

4. The combination with a machine for applying coating material to centers, in which is comprised a holder for coating material and means for moving centers to be coated beneath said holder, of a marking device, located in proximity to the body-coating mechanism, and consisting of a distributor having outlet ports, and means for varying the location of said outlets with relation to the surface of the coated goods being marked and means for supplying material to the marking device.

5. The combination with a machine for applying coating material to the bodies of centers, in which is comprised a holder for coating material and means for moving centers to be coated beneath said holder, of a marking device, located in proximity to the body-coating mechanism, for automatically applying marking material to the surfaces of the goods after their entire bodies have been coated, said marking device consisting of a conduit for the continuous supply of marking material, the conduit being provided with exit orifices for the escape of the marking material.

6. The combination with a machine for applying coating material to the bodies of centers, in which is comprised a holder for coating material and means for moving centers to be coated beneath said holder, of a marking device located in proximity to the body-coating mechanism, and consisting of a conduit for the continuous supply of marking material, said conduit being provided with exit orifices, means for supplying the marking material to the surfaces of the coated goods while the coating material is in a plastic condition, and means for heating the marking device.

7. A machine for stringing pasty material comprising a receptacle for said material provided with a suitable outlet opening, means for causing the receptacle to move in a circular path, and a device in the receptacle to effect the agitation of the material at or near said outlet opening.

8. A stringing machine for pasty material comprising a receptacle for said material having a discharge orifice, a device disposed at or near said orifice to agitate and expel said material, and means to cause the receptacle to move in a path eccentric to its orifice to deposit the material in a looped manner on a moving object.

9. In a chocolate stringing machine, a receptacle for containing the material and provided with a discharge orifice, means for moving the receptacle whereby the flow of material from the orifice may be directed either in a line concentric with or eccentric

to, the axis of the receptacle, and a device disposed at or near said orifice to agitate said material.

10. A machine for stringing pasty material comprising a receptacle for said material, provided with a suitable outlet opening, means for causing the receptacle to move in a curved path, and a device to effect the agitation of the material in the 10 receptacle.

11. A stringing machine for pasty material comprising a receptacle for said material having a discharge orifice, a device to agitate and expel said material and means 15 to cause the receptacle to move in a curved path.

12. The combination with a machine for applying plastic coating material to the bodies of candy centers, in which is comprised a holder for the plastic coating material to be applied to the centers, means for moving the candy centers to be coated beneath said holder, a marking device located in proximity to the body coating 20 mechanism, for containing the material to make the marks and for automatically dis- 25

tributing the marking material upon the surfaces of the goods, immediately after their bodies have been coated and while such coating is in a plastic state and means 30 for imparting movement to such distributor.

13. In a machine for stringing pasty material on the bodies of centers, a receptacle for said material provided with a suitable outlet, means to expel the material through 35 the outlet, means for moving the centers beneath said outlet and means for causing the material to be deposited upon the centers in a curved line.

14. A machine for stringing pasty material comprising a receptacle for said material provided with a suitable outlet opening, means for causing the receptacle to move in a curved path, and an expelling device to effect the expulsion of material from 40 the receptacle. 45

In testimony whereof I hereto affix my signature in presence of two witnesses.
